UNITED STATES PATENT OFFICE.

STANISLAW KIELAR, OF MILWAUKEE, WISCONSIN.

OFFICE-DESK APPLIANCE.

1,333,851.

Specification of Letters Patent. Patented Mar. 16, 1920.

Application filed May 31, 1919. Serial No. 301,066.

To all whom it may concern:

Be it known that I, STANISLAW KIELAR, a citizen of the United States of America, residing at Milwaukee, in the county of Milwaukee and State of Wisconsin, have invented certain new and useful Improvements in Office-Desk Appliances, of which the following is a specification.

The primary object of the invention is to provide a desk article serviceable for use both as a memorandum calendar for calling attention to appointments from day to day and retaining such data as well as furnishing a supply of suitable cards in position for writing thereon and readily removable singly whenever desired.

A further object of the invention is to provide a card holder for desks automatically positioning successive cards in writing position and having a pencil mounting means serving as a retainer against disassembling the device, although flexible at will for renewing the supply of cards.

A still further object of the invention is to provide in connection with a card holder for desks, a calendar memorandum strip in winding position readily changeable for viewing and use, tensioning means being provided for the operating means thereof.

With these general objects in view, the invention will be now fully described, reference being had to the accompanying drawings in which similar characters represent corresponding parts throughout the several views,

In the drawings,

Figure 1 is a front elevation of the invention positioned for use,

Fig. 2 is a transverse vertical sectional view of the invention taken upon line II—II of Fig. 3,

Fig. 3 is a top plan view of the invention,

Fig. 4 is a vertical longitudinal sectional view taken upon line IV—IV of Fig. 3,

Fig. 5 is a transverse sectional view taken upon line V—V of Fig. 3,

Fig. 6 is a rear elevational view of the calendar member with the rear plate and adjusting screw removed, and

Fig. 7 is a perspective view of one end portion of the base plate.

My invention broadly consists of a card holder 10 carried by a block 11 for seating upon a desk such as 12 while a casing 13 of

a calendar member is removably attached 55 inclined at the rear of the holder 10 and opposite in position to a removable pencil 14.

A card holder 10 comprising a base 15 countersunk within the block 11 and having a rectangular depression 16 for the detachable reception of the rectangular frame 17 forming the sides of the holder. A projecting lip 18 upon one end of the frame 17 fits within a socket 19 in one end of the base 15 while resilient posts 20 adjacent the opposite end of the base are adapted for the reception of the frame 17 therebetween. Outwardly projecting pins 21 upon the frame 17 are received within perforations 22 of the post 20 when the frame is seated in the depression 16 with the card holder assembled.

A platform 23 within the frame 17 is seated upon springs 24 tending to force the platform toward an inwardly projecting U-shaped flange 25 at the top of the frame 17 75 and whereby the uppermost one of a plurality of cards 26 upon the platform is positioned ready for writing thereon at the top of the holder 10. The flange 25 does not cover one end 27 of the frame 17 permitting 80 the removal of the uppermost card whenever desired, leaving the next card exposed for writing purposes.

Hangers or clips 28 and 29 upon the front side of the frame 17 are adapted for holding the pencil 14 preferably secured by a chain 30 to the clip 28. The clip 29 is pivoted on a stud 31 carried by the frame 17 normally overlying the adjacent post 20 and retaining the frame 17 from being removed from the depression 16. Upon removing the pencil 14, the clip 29 may be swung upwardly on the stud 31, releasing the post 20 therebeneath and permitting the post to spread outwardly for releasing the pins 21 and permitting upward and longitudinal movement of the frame 17 during its removal from the depression 16. The springs 24 being secured to the base 15 and the platform 23 being secured to said 100 springs, the refilling of the holder 10 with cards 26 is readily accomplished by mounting the cards upon the platform 23 and then replacing the frame 17 in the depression 16.

The calendar member 13 comprises a substantially rectangular casing having one end 32 bent for reception within an outwardly struck loop 33 in the rear side of the

frame 17, the calendar or casing 13 at such times being rearwardly inclined upon the frame in its normal operative position.

The calendar casing 13 has a removable rear plate 34 slidable therein while spaced rollers 35 are transversely journaled through the frame 13 having operating wheels 36 outwardly of the casing at the opposite sides thereof. The combined calendar and memorandum strip 37 wound upon the rollers 35 pass through spaced slots 38 in the forward side 39 of the casing 13 with exposed portions of the strip flatly engaging the central portion of the front of the casing 13 between said slots 38. Any suitable date designations such as 40 may be provided suitably spaced upon the strip 37 and upon turning either of the rollers 35 by means of its wheel 36, the strip 37 is moved in either direction required for bringing the desired portion of the strip viewable forwardly of the casing 13.

A cross-shaped follower 41 formed of resilient material fits within the casing 13 inwardly of the back plate 34 having curved arm portions 42 bearing upon the roller portions of the strip 37 carried by the rollers 35. A tensioning screw 43 threaded centrally through the plate 34 bears in a central socket 44 of the follower 41 and whereby the tension of the arms 42 upon the rolled strip is regulated at will.

The complete operation of the invention will be apparent from this detailed description thereof, the use of the pencil 14 upon the uppermost one of the cards 26 being already

set forth as well as the manner of disassembling the holder 10 for inserting a new supply of cards 26. The wheels 36 are turned for changing the position of the strip 37, each exposed portion of the strip having sufficient space for holding suitable notes or memoranda written thereon by the pencil 14 when desired, while the tension of the strip is regulated by the screw 43 so that the portion of the strip outwardly of the casing 13 will be maintained taut for readily writing thereon whenever desired.

While the form of the invention herein set forth is believed to be preferable, it will be understood that minor changes may be made therein without departing from the spirit and scope of the invention as claimed.

What I claim as new is:—

In combination with a card holder, a casing removably mounted inclined thereon having transverse slots spaced apart in the front side thereof, transverse rollers journaled within the casing, a memorandum calendar strip upon said rollers passing through said slots flatly engaging the intermediate portion of the casing side, the rear side of said casing being slidably removable, a cross-shaped resilient follower within the casing having curved arm portions seated upon the strip wound upon the rollers and having a central depression and a tensioning screw threaded through the rear side of the casing bearing in the said depression.

In testimony whereof I affix my signature.
STANISLAW KIELAR.
